UNITED STATES PATENT OFFICE.

CHARLES WESTER, OF NEW YORK, N. Y.

DESIGN FOR A BUTTON-HOOK.

SPECIFICATION forming part of Design No. 21,792, dated August 23, 1892.

Application filed July 14, 1892. Serial No. 440,077. Term of patent 7 years.

To all whom it may concern:

Be it known that I, CHARLES WESTER, a subject of the Emperor of Germany, and a resident of the city, county, and State of New York, have invented a new and useful Design 5 for Button-Hooks; and I do hereby declare that the following is a full and exact description thereof, reference being had to the accompanying drawing, and to the letters of reference 10 marked thereon, making a part of this specification.

The object of my invention is to produce a novel design for button-hooks.

The accompanying drawing presents a view 15 in elevation of a button-hook formed in accordance with my design.

The instrument as designed by me is composed of an open hook, a smooth and gently-tapering shank, an ornamented portion of the 20 shank, and a terminal portion. The ornamented portion of the shank is made substan-

tially cylindrical with a shallow groove *a*, formed about the same in a long spiral. A bead *b* may be formed at the hook end of the spiral groove and another bead *c* at the handle end of the groove. Between the bead *c* 25 and the terminal portion or handle I have formed the shank with a circumferential series of longitudinal plane faces *d d*, substantially as shown; but the main feature of my 30 design is the long spiral groove *a*.

I claim—

The design for a button-hook, herein shown and described.

In testimony whereof I have signed my 35 name to this specification in the presence of two subscribing witnesses.

CHARLES WESTER.

Witnesses:

A. N. JESBERA,
A. WIDDER.
